CLAIM

The ornamental design for a roof vent, as shown and described.

DESCRIPTION

FIG. 1 is a top isometric view of the roof vent;
FIG. 2 is a bottom isometric view of the roof vent of FIG. 1;
FIG. 3 is a top plan view of the roof vent of FIG. 1;
FIG. 4 is a bottom plan view of the roof vent of FIG. 1;
FIG. 5 is a right end elevation view of the roof vent of FIG. 1;
FIG. 6 is a left end elevation view of the roof vent of FIG. 1;
FIG. 7 is a back side elevation view of the roof vent of FIG. 1;
FIG. 8 is a front side elevation view of the roof vent of FIG. 1;
FIG. 9 is an enlarged view of a segment of FIG. 1;
FIG. 10 is an enlarged view of a segment of FIG. 2;
FIG. 11 is an enlarged view of a segment of FIG. 3; and,
FIG. 12 is an enlarged view of a segment of FIG. 4.
The broken lines illustrate portions of the roof vent and form no part of the claimed design.
